UNITED STATES PATENT OFFICE.

WALDO L. BATES, OF BOSTON, MASSACHUSETTS.

BAKER'S OVEN.

1,263,998.

Specification of Letters Patent. Patented Apr. 23, 1918.

Application filed December 7, 1917. Serial No. 205,922.

To all whom it may concern:

Be it known that I, WALDO L. BATES, a citizen of the United States, residing at Boston, in the county of Suffolk and State of Massachusetts, have invented certain new and useful Improvements in Bakers' Ovens, of which the following is a specification, reference being had to the accompanying drawings.

10 This invention relates to bakers' ovens and has for a primary object to provide simple and effective means for quickly heating the interior of the oven to a maximum degree, in the baking of bread, and for rapidly 15 cooling the oven for pastry baking.

It is another and more particular object of the invention to provide a baker's oven having a continuous flue extending under the bottom of the oven, around the rear end 20 thereof and longitudinally over the top of the oven to an outlet at the forward end, a damper plate for admitting the heat and products of combustion from the fire box directly into the flue beneath the oven, and 25 a cold air inlet damper operable to admit atmospheric air into said flue beneath the oven when the first named damper is closed.

It is a further general object of my invention to improve the construction of bakers' 30 ovens in the particulars above stated, without greatly increasing the cost of installation or erection of the oven.

With the above and other objects in view the invention consists in the improved construction, combination and arrangement of the several parts to be hereinafter more fully described, subsequently claimed and illustrated in the accompanying drawings in which similar reference characters designate 35 corresponding parts throughout the several views, and wherein—

Figure 1 is a longitudinal section through a baker's oven illustrating one embodiment of my invention;

40 Fig. 2 is a fragmentary vertical section of the forward end of the oven showing a slightly modified form of the hot air damper.

Referring in detail to the drawing, 5 and

6 designate respectively the upper and lower double walls of the oven which are supported and spaced apart by means of a plurality of metal bridge members or girders 7. These spaced walls are preferably formed of tiling as is usual in the construction of such ovens and provide upper and lower continuous longitudinally extending flues 8 and 9 respectively. To the rear ends of these flues, a communicating flue of sheet metal designated at 10 is suitably connected. 50 From the lowermost wall 6 of the oven proper at its rear end, a sheet metal wall 11 extends downwardly to the floor and constitutes the rear end wall of a heat chamber 12. This wall 11 at its upper end is provided with an opening in which a leg or extension 13 from the flue connection 10 is suitably connected. 55

14 designates the fire box which is mounted and arranged beneath the oven at the forward end thereof. An outer metal shell or casing 15 incloses the oven and the fire box and is provided at its forward end with suitable doors affording access to the doors on the forward end of the fire box when it is necessary to feed fuel into the latter. 60

16 designates the swinging or pivotally mounted oven door the free lower end of which is adapted for engagement in the closed position of the door with a horizontally disposed plate 17 extending between the forward end of the upper wall 6 and the front wall of the casing 15. This oven door may be mounted and arranged in any ordinary or approved manner and is preferably provided with the usual counter balancing weight whereby the door is returned to its normal closed position. 65

The top of the fire box 14 is spaced from the lowermost wall 6 as indicated at 18 and immediately below this space at the forward end of the fire box, a horizontal wall or plate 19 extends between the casing 15 and the front wall of the fire box. Upon this plate and contiguous to the fire box a damper plate 20 is pivotally mounted at its lower edge as at 21. One end of the rod or pivot of this plate is provided with a curved

arm 22 to which the rear end of a rod 23 is pivotally connected. This rod extends forwardly through an opening 24 in the front wall of the casing 15 and is provided with 5 a suitable hand hold whereby the rod may be conveniently actuated. In the position of this rod as seen in Fig. 1 of the drawings, the damper plate 20 is disposed in a vertical position and closes communication between the space 18 above the fire box and the forward end of the longitudinal flue 9.

The front wall of the casing 15 is further provided above the rod 23 with a cold air inlet opening 25 which is normally closed 15 by means of the pivoted damper plate 26.

In the operation of the device as shown in Fig. 1, when it is desirable to obtain a relatively high bottom or floor heat in the oven, as in the baking of bread, the rod 23 is pulled outwardly thereby swinging the damper plate 20 downwardly upon the horizontal plate 19. A portion of hot air and products of combustion will now pass forwardly over the top of the fire box 14 and 25 upwardly into the forward end of the flue 9, thence rearwardly beneath the oven to the vertical flue 10 and into the rear end of the upper flue 8. Finally, the products of combustion pass forwardly through this upper 30 flue and are liberated to the atmosphere through the outlet flue of stack 27 connected to the forward end of the flue 8, the stack 27 is of course equipped with a suitable damper so that the draft through the stack 35 may be regulated as desired. By thus causing the hot air to contact directly with the upper one of the lower walls 6, this wall will be very quickly and highly heated and the temperature of the oven increased to the 40 maximum degree. In the baking of pastries, it is of course desirable that the oven should be relatively cool and in such case the rod 23 is forced inwardly to raise the damper 20 to its closed position over the 45 forward end of the space 18 above the fire box, thereby cutting off communication between the space and the flue 9. The damper plate 26 is then moved to its open position so that atmospheric air will be drawn 50 through the opening 25 and the flues 9, 10 and 8 around the furnace. Thus the oven walls will be quickly cooled and the temperature of the baking chamber reduced to the desired degree. The products of combustion 55 and hot air from the fire box will now pass into the extension 13 of the flue 10 and be drawn directly into the rear end of the flue 8 and thence into the outlet stack 27.

In Fig. 2 of the drawing I have shown a 60 slightly modified form of the hot air damper, wherein a second horizontal plate 28 is arranged above and in spaced relation to the plate 19 and is provided with a plurality of spaced slots 29. A correspondingly

slotted valve plate 30, is slidable upon the 65 plate 29 and is provided with a central up-standing stud 31 to which the inner end of a lever 32 is loosely connected, said lever being pivotally mounted on the plate 29 as at 33 and having an arm 34 extending outwardly through an opening in the front wall of the casing 15. It will be readily understood that by moving the arm 34 laterally in one direction, the plate 30 will be moved to register the slots or openings 70 therein with the slots in the plate 29 so that the hot air may pass from the fire box into the forward end of the flue 9. The cold air damper plate is of course also provided as 75 in the previously described form of the device.

From the foregoing description taken in connection with the accompanying drawings, the construction, manner of operation and several advantages of my invention will 80 be clearly and fully understood. It will be noted that the device consists of but few parts, and will not materially add to the cost of installation of the oven. The device provides means for easily and quickly regulating the temperature of the oven without necessitating an additional consumption of fuel. The operating cost is therefore reduced to a minimum. I have above described two forms of the hot air damper, 85 which I have found very satisfactory in practical use. It will be understood however that this damper may be otherwise constructed and arranged and the various other structural parts of my invention may also 90 be somewhat modified in form and proportion. Accordingly, I reserve the privilege of resorting to all such legitimate changes as may be fairly embodied within the spirit and scope of the invention as claimed. 95

Having thus fully described my invention, what I desire to claim and secure by Letters Patent is:

1. In a baker's oven spaced upper and lower walls providing longitudinally extending flues above and below the oven chamber, the space below the oven at the rear end thereof constituting a heat chamber, a fire box arranged below the oven at its forward end and communicating with 110 said heat chamber, a flue connecting the rear ends of the longitudinal flues and having an extension communicating with said heat chamber, and a damper to open and close communication between the heat chamber 115 and the forward end of the lower longitudinal flue.

2. In a baker's oven spaced upper and lower walls providing longitudinally extending flues above and below the oven chamber, the space below the oven at the rear end thereof constituting a heat chamber, a fire box arranged below the oven at 120

its forward end and communicating with said heat chamber, a flue connecting the rear ends of the longitudinal flues and having an extension communicating with said heat chamber, and a damper to open and close communication between the heat chamber and the forward end of the lower longitudi-

nal flue, and a cold air inlet damper disposed above said first named damper in spaced relation to the forward end of the lower longitudinal flue and in line therewith.

In testimony whereof I hereunto affix my signature.

WALDO L. BATES.
